(57) **CLAIM**

The ornamental design for a pedestal, as shown and described.

DESCRIPTION

FIG. 1 is a top perspective view of a pedestal;
 FIG. 2 is a front view of the pedestal of FIG. 1;
 FIG. 3 is a left side view of the pedestal of FIG. 1; and,
 FIG. 4 is a right side view of the pedestal of FIG. 1.
 Portions of the drawings shown in broken lines form no part
 of the claimed design.

1 Claim, 4 Drawing Sheets
